SAMUEL BURK, OF NEW YORK, N. Y.

WINDOW-OPERATING MECHANISM.

1,177,013.

Specification of Letters Patent. Patented Mar. 28, 1916.

Application filed August 20, 1915. Serial No. 46,457.

To all whom it may concern:

Be it known that I, SAMUEL BURK, a citizen of the United States, and a resident of New York, borough of Brooklyn, county of Kings, and State of New York, have invented certain new and useful Improvements in Window-Operating Mechanism, of which the following is a full, clear, and exact specification.

10 This invention relates to a class of apparatus adapted to be used in conjunction with windows.

My invention has for its object primarily to provide a form of mechanism designed 15 to be applied to the window of a building, or other structure whereby the sash may be easily raised and lowered to any desired height without requiring the use of weights and cords as is incident to the methods ordinarily employed, and which is so constructed that both of the sashes may be locked when in open, or closed positions without liability of being surreptitiously unlocked, the mechanism being adaptable for 20 use in conjunction with windows having one, or a number of sashes.

The invention consists essentially of providing a stationary casing in proximity to the adjoining ends of the sashes of the 25 window having vertically disposed toothed racks on the outer edges of one of the corresponding stiles of the frames of the sashes, and in this casing are arranged one, or a number of independently rotatable toothed 30 wheels each meshing with one of the racks. Connected to each of the toothed wheels is a spring normally serving to revolve its toothed wheel so that the sash operable thereby will be yieldingly forced to a closed 35 position, thus when the lower sash is raised, or the upper sash is lowered the movements will be against the tension of the springs.

Another object of the invention is to provide means serving to permit the sashes to 40 be locked against accidental movements when in raised or lowered positions, and which is of a form to prevent the locking means from being surreptitiously unlocked from the outside of the window; and a 45 further object of the invention is to provide an operating mechanism for windows of a simple, efficient and durable construction.

A practical embodiment of the invention is represented in the accompanying drawing 50 forming a part of this specification in which similar characters of reference indicate cor-

responding parts in all the views, the said invention being more fully described hereinafter, and then pointed out in the claims at the end of the description.

In the drawing, Figure 1 is a fragmentary view, partly in section of a window with one form of operating mechanism embodying my invention applied thereto. Fig. 2 is an enlarged front elevation of the operating mechanism. Fig. 3 is a section taken on the line III—III of Fig. 2. Fig. 4 is a detail section taken on the line IV—IV of Fig. 3, and Fig. 5 is a section, partly in detail, taken on the line V—V of Fig. 2.

The mechanism has a casing 10 composed of a supporting plate, as 11, having a vertically disposed elongated slot 12 centrally therethrough and a vertically disposed cut-out 12^a in one of its edges, and projecting 60 at a right angle from the upper part of this supporting plate is an overhanging transverse bar 13. On the edge of the bar 13 opposite to the supporting plate is an apertured lug, as 14, and spaced from this lug 65 on the bar is a lug, or stop 15. Also extending from the supporting plate 11 underneath the bar 13 is a plate 16 which is somewhat wider than the bar, and transversely in this plate is a slot 17 in register with the 70 aperture of the lug 14 of the bar 13 as well as being alined with the free lengthwise edge of this bar. Projecting downwardly 75 from the underside of the plate 16 are two spaced extensions 18 and 19 in the upper 80 parts of both of which are registered recesses forming the lower parts of the slot 85 17 of the plate 16. Integral with the lower end of the extension 18 is a boss, as 21, having a recess 22 in one of its faces, and integral with the lower end of the extension 19 is a second boss, as 23, having a recess 24 in its face which is opposite to the recessed face of the boss 21. The recessed 90 bosses are spaced apart in parallel arrangement, and journaled in bearings centrally of the bosses is a shaft 25.

The casing 10 is arranged in a recess, as 95 26, provided in the frame 27 of the window of a building, or other structure, the window having upper and lower sashes, as 28 and 29, and this casing is held stationary in the recess by fastening the supporting plate 11 by screws, or otherwise to the frame of the window. As shown, the casing 10 is disposed adjacent to the adjoining upper and lower rails of the sashes of the window, and

on the shaft 25 between the bosses 21 and 23 is held a toothed wheel 30 which is in mesh with a toothed rack 31 preferably countersunk in the opposed edge of the 5 frame of the upper sash 28 of the window. Also on the shaft 25, and journaled in the bearing of the recessed boss 23 is a sleeve 32 which is freely rotatable on the shaft as well as being rotatable in this recessed 10 boss, and keyed on the sleeve adjacent to the recess of the boss 23 is a toothed wheel 33 in mesh with a toothed rack 34 which is countersunk in the opposed edge of the lower sash 29 of the window. In the recess 22 of 15 the boss 21 and encircling the shaft 25 is a spiral spring 35 having one end fastened to this shaft, at 35^a, and the other end of the spring is fastened to the boss, at 35^b. In the recess 24 of the boss 23 and encircling 20 the sleeve 32 is another spiral spring 36 having one end held, at 36^a, to this sleeve, and the other end of the spring is secured, at 36^b, to the boss. The spring 35 is tensioned for normally serving to rotate the 25 shaft 25 and the toothed wheel 30 to force the rack 31 and the upper sash 28 upwardly to a closed position in the frame of the window, while the spring 36 is tensioned for normally serving to revolve the sleeve 32 30 and the toothed wheel 33 to force the rack 34 and the lower sash 29 downwardly to a closed position in the frame of the window. Thus when the upper sash is lowered the 35 wheel 30 and the shaft 25 against the tension of the spring 35, and when the lower sash is raised the rack 34 will be guided to rotate the wheel 33 and the sleeve 32 against the tension of the spring 36.

40 Serving as means to hold the sashes against accidental movement when in raised or lowered positions as well as preventing the sashes from being surreptitiously opened from the outside of the window, I provide a locking element, as 37. The locking element 37 has a bar 38 which is freely movable in the slot 17 of the plate 16 of the casing 10. The locking bar 38 is of a width so that its upper edge is in movable contact with the free edge of the bar 13 of the casing and so that its lower edge will extend in the spaces between the teeth of the wheels 30 and 33, and the lower part of the locking bar is tapered downwardly 50 to fit snugly, but be freely movable between the teeth of these wheels. The bar 38 is somewhat longer than the width of the casing 10 so that one end thereof will extend through an opening in the frame of 55 the window inside thereof, this opening, not shown, leading from the recess 26 of the frame, and on this extending end of the bar is a handle, as 39, to allow the bar to be conveniently pushed and pulled inwardly 60 and outwardly of the opening of the recess 65

for slidably guiding the bar in the slot 17 of the plate 16 of the casing. Projecting upwardly from the top of the locking bar 38 is a lug 40 adapted to abut against the stop 15 of the bar 13 of the casing, and extending from this lug is a rod 41 having its other end part freely movable in the aperture of the lug 14 of the bar 13. When the locking bar 38 is forced inwardly of the casing the rod 41 will be guided through the 70 aperture of the lug 14, and serving to normally force the locking bar outwardly of the casing encircling the rod 41 between the lug 40 and the apertured lug 14 is a spiral spring 42. As above explained the 75 tapered lower edge of the locking bar 38 is normally disposed in one of the spaces between the teeth of the wheels 30 and 33 to prevent their rotation and for locking the window sashes against accidental movement. The handle 39 and the adjacent part of the locking bar 38 will then extend some distance outwardly of the casing 10 and outwardly of the frame of the window. To permit the locking bar 38 to be freed of its 80 engagement with the toothed wheels when the bar is forced inwardly of the casing and for also permitting the sashes of the window to be raised and lowered, as will be hereinafter more fully explained, in the 85 lower edge of the locking bar are two notches, or recesses 43 and 44. Both of the notches 43 and 44 are somewhat wider than the toothed wheels 30 and 33, and these notches are spaced apart substantially the 90 same distance as the spacing between the toothed wheels so that when the locking bar 38 is guided inwardly of the casing 10 the lower edge of this bar will be freed of engagement with the teeth of the wheels 95 100 which will be disposed in these notches. The releasing of this engagement between the locking bar and the toothed wheels will permit the sashes of the window to be freely 105 raised and lowered.

110 In order to releasably hold the locking bar 38 against accidental movement when directed inwardly of the casing, in a recess 45 provided in the extension 19 of the plate 16 of the casing, is a transversely disposed bolt, or pin 46 which is movably held in 115 openings in this extension so that one end of the bolt will pass into an orifice, as 47, arranged in the locking bar 38 when the bar is guided inwardly of the casing. On 120 the central part of the bolt 46 in the recess 45 is rigidly held a wheel 48 having part of its peripheral edge cut-out in a tapered fashion, as at 49, to provide the wheel with a cam edge. Encircling one end part of the 125 bolt 46 between the cam edged wheel 48 and one of the walls of the recess 45 is a spiral spring 50 normally serving to force the other end of the bolt outwardly of this recess into yielding contact with the locking bar 38 so 130

that this end of the bolt will pass into the orifice 47 of the locking bar when the bar is guided inwardly of the casing. Also in the recess 45 is an operating lever 51 which is fulcrumed, at 52, to the extension 19 of the plate 16 of the casing 10. This lever is of a length so that one of its ends is movably seated in the tapered cut-out part 49 of the cam-edged wheel 48 and so that the other end of the lever extends outwardly of the recess 45, this end terminating with a handle 53 which is curved in a direction away from the locking bar 38.

In practice when the sashes of the window are closed and locked against being surreptitiously opened from the outside of the window the bar 38 of the locking element 37 is disposed outwardly of its slot 17 of the plate 16 of the casing. The tension of the spring 42 will then force the rod 41 and the lug 40 of this locking bar toward the lug 15 of the bar 13 of the casing. The spring actuated bolt 46 will also be freed of engagement with the orifice 47 of this locking bar as well as being forced inwardly of the recess 45 against the tension of its spring 50. The lower edge of the locking bar 38 will also be disposed between the teeth of the wheels 30 and 33 to prevent their rotation, and the sashes of the windows will thereby be locked against accidental movement. When it is desired to raise and lower the sashes one or both of the sashes are moved accordingly after the locking bar is guided inwardly of the casing by pushing its handle 39. With this movement of the locking bar the rod 41 will be directed inwardly of the aperture of the lug 14 of the bar 13 of the casing against the tension of the spring 42, and when the locking bar is forced a proper distance in the slot 17 of the plate 16 the bolt 48 will be forced by the tension of the spring 50 into the orifice 47 of the locking bar. The end of the lever 51 in contact with the tapered cut-out part 49 of the cam wheel 48 will likewise be swung toward the locking bar, and, as above explained, with this movement of the locking bar its lower edge will be released from engagement with the toothed wheels 30 and 33 by the toothed wheels being received in the notches 43 and 44 of the locking bar. The sashes of the window may then be adjustably moved as desired, for instance if the upper sash is lowered the movement of its rack will rotate the shaft 25 and the toothed wheel 30 against the tension of the spiral spring 35 in the boss 21, and if the lower sash is raised the movement of its rack will rotate the sleeve 32 and the toothed wheel 33 against the tension of the spiral spring 36 in the boss 23. The sashes may then be again releasably locked against movement by forcing the handle 53 of the lever 51 in a direction toward the locking

bar 38. The other end of this lever will then be swung in an opposite direction for moving the cam wheel 48 toward the supporting plate 11 of the casing and for forcing the bolt 46 from the orifice 47 of the locking bar. The tension of the spring 42 will thereby cause a reverse movement of the rod 41 and the locking bar 38 so that the lower edge of the locking bar will be reseated in the teeth of the wheels 30 and 33 to lock these wheels against movement as well as preventing the sashes from being moved. By the employment of my mechanism in this manner the sash of the windows of buildings or other structures may be easily raised and lowered to any desired heights without requiring the use of weights and cords, and the sashes may be held in locked positions without liability of being surreptitiously unlocked from outside of the building in view of the mechanism being applied to the frame of the window as well as being operable only from the interior of the window.

In the foregoing description, I have embodied the preferred form of my invention, but I do not wish to be understood as limiting myself thereto, as I am aware that modifications may be made therein without departing from the principle, or sacrificing any of the advantages of this invention, therefore I reserve to myself the right to make such changes as fairly fall within the scope thereof.

Having thus described my invention, I claim as new and desire to secure by Letters Patent:—

1. In a window operating mechanism, a casing adapted to be held adjacent to the sash of a window having a vertically disposed stationary toothed rack, a toothed wheel rotatably held in the casing, and meshing with the toothed rack, a spring actuated locking bar movable inwardly and outwardly of the casing so as to engage and be disengaged from the toothed wheel, the said bar being normally in engagement with the toothed wheel to prevent rotation of the wheel and to prevent movement of the toothed rack as well as the sash when the bar is disposed outwardly of the casing, spring actuating means in the casing, adapted to yieldingly engage the bar when forced inwardly of the casing to hold the bar free of engagement with the toothed wheel whereby the sash may be raised or lowered, and means in the casing, adapted to be manually operated for releasing the engagement of the spring actuating means with the locking bar so that the locking bar will be reversely forced by its spring into engagement with the toothed wheel, substantially as set forth and for the purpose specified.

2. In a window operating mechanism, a

casing adapted to be held adjacent to the sash of a window having a vertically disposed stationary toothed rack, a toothed wheel rotatably held in the casing, and meshing with the toothed rack, a spring in the casing normally serving to rotate the wheel for yieldingly forcing the sash to a closed position, a spring actuated locking bar movable inwardly and outwardly of the casing so as to engage and be disengaged from the toothed wheel, the said bar being normally in engagement with the toothed wheel to prevent rotation of the wheel and to prevent movement of the toothed rack as well as the sash when the bar is disposed outwardly of the casing, a spring actuated bolt in the casing, adapted to yieldingly engage the bar when forced inwardly of the casing to hold the bar free of engagement with the toothed wheel whereby the sash may be raised or lowered, and means in the casing, adapted to be manually operated for releasing the engagement of the bolt with the locking bar so that the locking bar will be reversely forced by its spring into engagement with the toothed wheel, substantially as set forth and for the purpose specified.

3. In a window operating mechanism, a casing adapted to be held adjacent to the sash of a window having a vertically disposed stationary toothed rack, a toothed wheel rotatably held in the casing, and meshing with the toothed rack, a spring in the casing normally serving to rotate the wheel for yieldingly forcing the sash to a closed position, a spring actuated locking bar movable inwardly and outwardly of the casing so as to engage and be disengaged from the toothed wheel, the said bar being normally in engagement with the toothed wheel to prevent rotation of the wheel and to prevent movement of the toothed rack as well as the sash when the bar is disposed outwardly of the casing, a spring actuated bolt in the casing, adapted to yieldingly engage the bar when forced inwardly of the casing to hold the bar free of engagement with the toothed wheel whereby the sash may be raised or lowered, and a lever in the casing, adapted to be manually operated for releasing the engagement of the bolt with the locking bar so that the locking bar will be reversely forced by its spring into engagement with the toothed wheel, substantially as set forth and for the purpose specified.

4. In a window operating mechanism, a casing adapted to be held adjacent to the adjoining parts of the upper and lower sashes of a window, each having a vertically disposed stationary toothed rack, two toothed wheels rotatably held in the casing, and one meshing with each of the toothed racks to permit the sashes to be indepen-

ently or simultaneously raised and lowered, a spring actuated locking bar movable inwardly and outwardly of the casing so as to engage and be disengaged from both of the toothed wheels, the said bar being normally in engagement with the toothed wheels to prevent rotation of the wheels and to prevent movement of the toothed racks as well as the sashes when the bar is disposed outwardly of the casing, a spring actuated bolt in the casing, adapted to yieldingly engage the bar when forced inwardly of the casing to hold the bar free of engagement with the toothed wheels, and means in the casing, adapted to be manually operated for releasing the engagement of the bolt with the locking bar so that the locking bar will be reversely forced by its spring into engagement with the toothed wheels, substantially as set forth and for the purpose specified. 80

5. In a window operating mechanism, a casing adapted to be held adjacent to the adjoining parts of the upper and lower sashes of a window each having a vertically disposed stationary toothed rack, two toothed wheels rotatably held in the casing, and one meshing with each of the toothed racks to permit the sashes to be independently or simultaneously raised and lowered, a spring actuated locking bar movable inwardly and outwardly of the casing so as to engage and be disengaged from the toothed wheels, the said bar being normally in engagement with the toothed wheels to prevent rotation of the wheels and to prevent movement of the toothed racks as well as the sashes when the bar is disposed outwardly of the casing, a spring actuated bolt in the casing, adapted to yieldingly engage the bar when forced inwardly of the casing to hold the bar free of engagement with the toothed wheels, and a lever in the casing, adapted to be manually operated for releasing the engagement of the bolt with the locking bar so that the locking bar will be reversely forced by its spring into engagement with the toothed wheels, substantially as set forth and for the purpose specified. 95

6. In a window operating mechanism, a casing adapted to be held adjacent to the adjoining parts of the upper and lower sashes of a window each having a vertically disposed stationary toothed rack, two spaced recessed bosses in the casing, a shaft journaled in the bosses, two spaced toothed wheels held on the shaft, and one meshing with each of the toothed racks to permit the sashes to be independently or simultaneously raised and lowered, spring actuated means in each boss normally serving to rotate each wheel for yieldingly forcing the sashes to closed positions, a spring actuated locking bar movable inwardly and outwardly of the casing so as to engage and be disengaged from the toothed wheels, the said 130

bar being normally in engagement with the toothed wheels to prevent rotation of the wheels and to prevent movement of the toothed racks as well as the sashes when the bar is disposed outwardly of the casing, and spring actuated means in the casing, adapted to yieldingly engage the bar when forced inwardly of the casing to hold the bar free of engagement with the toothed wheels, and said means being manually operable for releasing its engagement with the locking bar so that the locking bar will be reversely forced by its spring into engagement with the toothed wheels, substantially as set forth and for the purpose specified.

7. In a window operating mechanism, a casing adapted to be held adjacent to the adjoining parts of the upper and lower sashes of a window, each having a vertically disposed stationary toothed rack, two spaced recessed bosses in the casing, a shaft journaled in the bosses, two spaced toothed wheels held on the shaft, and one meshing with each of the toothed racks to permit the sashes to be independently or simultaneously raised and lowered, spring actuated means in each boss serving to rotate each wheel for yieldingly forcing the sashes to closed positions, a spring actuated locking bar movable inwardly and outwardly of the casing so as to engage and be disengaged from the toothed wheels, the said bar being normally in engagement with the toothed wheels to prevent rotation of the wheels and to prevent movement of the toothed racks as well as the sashes when the bar is disposed outwardly of the casing, a spring actuated bolt in the casing, adapted to yieldingly engage the bar when forced inwardly of the casing to hold the bar free of engagement with the toothed wheels, and a lever in the casing, adapted to be manually operated for releasing the engagement of the bolt with the locking bar so that the locking bar will be reversely forced by its spring into engagement with the toothed wheels, substantially as set forth and for the purpose specified.

40 This specification signed and witnessed this nineteenth day of August A. D. 1915.

locking bar so that the locking bar will be reversely forced by its spring into engagement with the toothed wheels, substantially as set forth and for the purpose specified.

8. In a window operating mechanism, a casing adapted to be held adjacent to the adjoining parts of the upper and lower sashes of a window each having a vertically disposed stationary toothed rack, two spaced recessed bosses in the casing, a shaft journaled in the bosses, two spaced toothed wheels held on the shaft, and one meshing with each of the toothed racks to permit the sashes to be independently or simultaneously raised and lowered, spring actuated means in each boss serving to rotate each wheel for yieldingly forcing the sashes to closed positions, a spring actuated locking bar movable inwardly and outwardly of the casing so as to engage and be disengaged from the toothed wheels, the said bar being normally in engagement with the toothed wheels to prevent rotation of the wheels and to prevent movement of the toothed racks as well as the sashes when the bar is disposed outwardly of the casing, a spring actuated bolt in the casing, adapted to yieldingly engage the bar when forced inwardly of the casing to hold the bar free of engagement with the toothed wheels, and a lever in the casing, adapted to be manually operated for releasing the engagement of the bolt with the locking bar so that the locking bar will be reversely forced by its spring into engagement with the toothed wheels, substantially as set forth and for the purpose specified.
